UNITED STATES PATENT OFFICE.

SYDNEY McNAMARA AND WILLIAM NICHOLSON, OF NEW YORK, N. Y.

DESIGN FOR A TEACUP.

Application filed December 3, 1923. Serial No. 7,942. Term of patent 7 years.

To all whom it may concern:

Be it known that we, SYDNEY McNAMARA and WILLIAM NICHOLSON, subjects of the King of Great Britain, residing at New York city, State of New York, have invented a certain new, original, and ornamental Design for Teacups, of which the following is a description, reference being had to the accompanying drawing, forming a part thereof.

Fig. 2 is a top plan view of the cup;

Figs. 3, 4 and 5 are vertical sectional views on the line 3—3, 4—4 and 5—5, respectively, of Fig. 2.

We claim:

The ornamental design for a tea cup, as shown.

SYDNEY McNAMARA.
WILLIAM NICHOLSON.
